CLAIM

The ornamental design for egg mold, as shown and described.

DESCRIPTION

FIG. 1 is a perspective view of the egg mold showing my new design;

FIG. 2 is a top view thereof;

FIG. 3 is a front view thereof, the rear view being identical to the front view;

FIG. 4 is a right side view thereof;

FIG. 5 is a rear view thereof;

FIG. 6 is a left side view thereof; and,

FIG. 7 is a bottom view thereof.

The broken lines in the drawings are for illustrative purposes only and form no part of the claimed design.
